ENGINEER'S AND DRAFTSMAN'S LOOSE LEAF SKETCH AND PRINT CASE

Filed Dec. 29 1921

Patented Mar. 16, 1926.

1,577,056

UNITED STATES PATENT OFFICE.

CARL BJORK, OF WILMINGTON, CALIFORNIA.

ENGINEER'S AND DRAFTSMAN'S LOOSE-LEAF SKETCH AND PRINT CASE.

Application filed December 28, 1921. Serial No. 525,368.

To all whom it may concern:

Be it known that I, CARL BJORK, a citizen of the United States, residing at Wilmington, in the county of Los Angeles and State 5 of California, have invented a new and useful Engineer's and Draftsman's Loose-Leaf Sketch and Print Case, of which the following is a specification.

This invention includes a device which 10 may be put to any use such as loose leaf holder, engineer's or draftsman's case, loose leaf case, card holder, printing frame for blue prints or photographs and draftsman's table and T-square.

15 An object of the invention is to provide a device adapted to hold loose leaf memoranda or other sheets flat and to protect the same; to provide for convenience of inserting and withdrawing the sheets from the case; to 20 provide a satisfactory combined cover and closure for the case; to also provide a satisfactory rain and sun shield for the exposed sheet when the case is open; to provide means whereby an engineer or draftsman 25 may facilitate his work in the open field.

The invention is not limited to the use of engineers or draftsmen as will appear from the accompanying description.

The case may be made of any size or 30 shape and of any suitable material.

The case is also adapted to hold drawing instruments and artist's colors.

The invention is broadly new, basic and pioneer in that I provide a case one end and 35 the top of which are mainly open and provide a platform or follower inside such case adapted to hold the leaves flat against ledges at the edges of the open top and a cover is provided to close the open end and cover 40 the open portion of the open top, and also to serve as a T-square in connection with the sides or closed end of the case.

Cheapness and simplicity of construction 45 are other objects.

Other objects, advantages and features of invention may appear from the accompanying drawing, the subjoined detail description and the appended claims.

The accompanying drawing illustrates the 50 invention.

Figure 1 is a perspective view of the invention in use as an engineer's or draftsman's sketching pad. Parts are broken away to expose interior construction.

55 Fig. 2 is a side elevation of the case showing the cover adjusted as a sun or rain

shade, portions being broken away to contract the view.

Fig. 3 is an end view of the parts as shown in Fig. 1. 60

Fig. 4 is an end view showing the platform or follower located in position to release the loose leaves of the tablet.

Fig. 5 is a side elevation showing the case used in desk form. 65

Fig. 6 is a plan view of the case with the cover in place.

Fig. 7 is a bottom plan of the follower.

Fig. 8 is a longitudinal sectional view on line $\alpha\beta$, Fig. 6. 70

Fig. 9 is a fragmental end view showing a modified form of means to hold the follower in leaf releasing position.

Fig. 10 is a plan view of the cover in use as a T-square and adapted to be slid along 75 the longitudinal sides of the holder.

Fig. 11 is a plan view of the cover in use as a T-square and adapted to be slid along the closed end of the holder.

The case is of the open top type and is 80 preferably constructed rectangular in shape with a solid bottom 1, parallel solid side walls 2 and a solid end wall 3. The end opposite the end wall 3 is provided with an opening 4 almost coextensive with the space between the side walls 2. Inward extensions or end retainers 5 extend from the free ends of the side walls and serve as retainers to hold the angular end projection 6 of the cover 7; said end projection 6 is formed at 85 right angles to the cover 7 and is rectangular in shape and forms an end closure for the open end of the case between said extensions, and said cover 7 is also adapted to close the opening 8 in the top of the case 90 which opening is enclosed by the marginal ledges 9 that form a frame around the opening 8, and are secured to the end and side walls of the case. Inside the case a platform or follower 10 is resiliently supported and 95 arranged to operate toward and from the marginal ledges 9 and is adapted to frictionally hold a tablet 11 between its upper surface and said marginal ledges. It being understood that the tablet 11 may be a plurality of loose leafs or other construction 100 well known in the art.

Bow springs 12 having their ends formed with upturned runners 13 are fixed to the underside of the follower and are adapted to 110 pass through the space between the inward extensions or end retainers 5. The spaces 14

above the end retainers 5 allow the tablet or loose leafs 11 to be admitted to and to be withdrawn from the case.

Means are provided whereby the platform 5 or follower 10 may be easily and securely locked or held in the leaf releasing position or away from the marginal ledges, and these means are preferably in the form of a catch 15 fixed to and extending down from the 10 middle of the follower, and a movable latch 16 which may be readily shifted to and from the path of the catch when the follower is fully pressed in. Said latch, as shown in Figs. 1, 3, 4 and 8 comprises a roller 17 movable by gravity along two ways 18 formed by the straps 19 that are fixed to the bottom 1 of the case.

The roller 17 is arranged to roll from end to end of the ways according as the case is 20 tilted from one side to the other and when the latch roller rolls to one side it is in the path of the catch and when it is rolled to the other side it is out of the path of the catch.

In Fig. 9 I have shown a modified form of 25 latch which comprises a roller 17' movable by gravity along two ways 18' in the flanges 19' that are fixed to the bottom of the case.

Pencil holders 20 are also shown connected to the follower and the same comprises a 30 single strip of spring metal fixed by a central pivot 21 to the follower between the two bends 22, which are at each end of said strip and adapted to accommodate a pencil between the spring strip and the follower so 35 that a pencil or other drawing instrument may be inserted and will be held by the spring against the follower. Artists' colors or other drawing instruments may be held by the bends 22 as desired.

40 Various devices may be used in combination with this appliance, as for instance, a transparent protractor 23 may be inscribed on the cover 7 and provided with holes 24 through which a pencil point may be inserted for the purpose of marking points and drawing lines in a well known manner; for the purpose of clearness only a few of the degree lines are shown, it being apparent that any number of desired markings 45 may be made without departing from the spirit of the invention.

The cover is preferably provided along its edges with scales 25, 26 and may be made transparent as of celluloid and the marginal ledges 9 may also be provided with scales 27, 28. If desired, the protractor may be made on a separate sheet and inserted in the case.

60 The angular end projection 6 which forms the end closure for the open end of the case also serves to support the case at a desirable angle for writing when the pad or case is laid upon a table.

65 The end retainers 5 are also adapted to receive and hold the cover 7 in position so

as to form a rain and sun shield for the exposed sheet when the case is open, as shown in Fig. 2.

The use of the device as a photographic printing frame is obvious from the foregoing, the follower being adapted to be pressed in by pressure of the thumbs or fingers thereon and the latch means engaged to hold the follower in pressed-in position to allow the tracing or transparent sheet above 70 the chemical paper to be inserted into the case, then the follower will be released.

The cover has a further advantage of being used in connection with a compass, not shown, as a cross bearing for obtaining ship's 80 positions at sea. This is attained by inserting a point, not shown, in the central hole 29 of the protractor 23 and inserting other points, not shown, in desired holes of the protractor to bear on known land objects.

The cover has a further advantage in that it is adapted to be inserted between the tablet 11 and the marginal ledges 9 and may be withdrawn a predetermined distance so as to expose for use a small strip of the tablet. 90 The cover when used in this manner serves as a guide for writing and also prevents soiling the tablet which oftentimes occurs by resting soiled hands upon the tablet during writing operation.

Another advantage gained by constructing and arranging the parts of my engineer's and draftsman's loose leaf sketch and print case as above set forth is that when an engineer is in the field my device affords him a compact and substantially complete drawing outfit that will assist him in making readable sketches. In many instances engineers in the field have been handicapped in making sketches because they did not have means accessible with which they could draw straight and parallel lines and normal lines extending therefrom. The quadrille sketch paper has to some extent served this purpose but with my sketch device plain paper may be used and the cover 7 may be used as a T-square by reason of the angular end projection 6 being adapted to cooperate with either the closed end or the longitudinal sides of the case as shown in Figs. 10 110 and 11.

I claim:

1. A case having a bottom, an open top, side walls, an open end and an end wall; marginal ledges secured to said end and side walls forming a frame around the open top; a detachable cover adapted to form a closure for said open top, and having an angular end projection to close said open end and providing means whereby said cover may be used as a T-square with said case; a follower in said case adapted to hold a tablet between its upper surface and said ledges; resilient means adapted to hold said follower against said ledges; and means to hold 130

said follower away from said ledges for the purpose set forth.

2. A case having an open top, an open end, a bottom, side walls and an end wall; 5 marginal ledges which form a frame around the open top; means for removably securing a tablet in said case; and a cover adapted to close said open top and having an angular end projection which is adapted to close 10 said open end, said cover being provided along its edges with scales and having holes designating degree lines of a protractor.

3. A case having an open top; marginal ledges which form a frame around the open 15 top; a follower in said case; and gravity operated latch means adapted to hold said follower away from said ledges and adapted to be released by pressure on said follower and by gravity.

20 4. A case having side walls, an end wall, an open top and an open end; means for holding a tablet in said case, and a cover having an angular projection which is adapted to form a closure for the open portions 25 of said case and also adapted to be used as a T-square in connection with the sides and end of the case.

5. In a device of the character described, a case having a bottom, an open top, side 30 walls and an end wall; marginal ledges secured to said end and side walls; a follower in said case; springs fixed to said follower and adapted to resiliently hold said follower against said ledges; a catch secured to said 35 follower; and a movable latch mounted on the bottom of the case that is adapted to engage said catch and hold the follower away from the marginal ledges for inserting and removing a tablet from the case.

40 6. In a device of the character set forth, a case; means for holding a tablet in said case whereby the top sheet of said tablet will be exposed for use; a cover adapted to form a closure for said case, said cover having 45 an angular projection adapted for use in connection with said case as a T-square; and means on said case adapted to retain said cover in position for use as a rain and sun shield for the exposed sheet when the 50 case is open.

7. A case having an open top, a bottom, side walls and an end wall; marginal ledges which form a frame around said open top; a follower resiliently mounted in said case 55 and adapted to hold a tablet against said ledges; and means comprising a latch, flanges fixed to the bottom of said case and

having ways, a roller mounted in said ways adapted to engage said latch for holding said follower away from said ledges when 60 inserting and withdrawing the tablet from said case.

8. A case having a bottom, an open top, side walls and an end wall; marginal ledges secured to said end and side walls forming 65 a frame around said open top; a detachable cover adapted to form a closure for said case; a follower in said case; resilient means adapted to hold said follower against said ledges; means to hold said follower away 70 from said ledges comprising a catch fixed to and extending down from said follower, and a movable latch adapted to be moved by gravity to and from the path of said catch for the purpose set forth. 75

9. A case having an open top; marginal ledges which form a frame around the open top; a follower in said case; resilient means adapted to hold said follower against said 80 ledges; a cover adapted to close said open top, and having an angular end projection whereby said cover may be adapted for use as a T-square with said case; and a spring metal strip having bends at each end and being fixed to said follower between said 85 bends, said bends being adapted to hold drawing instruments and artists' tools against said follower.

10. A case having an open top, marginal ledges which form a frame around the open 90 top; a follower resiliently mounted in said case and being adapted to hold a tablet between its upper surface and said ledges and also adapted to be pressed away from said ledges by pressure on the top of said follower; and gravity operated latch means to hold said follower away from said ledges after said follower has been pressed away from said ledges, and to release said follower. 95

11. A case having an open top, side walls, and an end wall; ledges secured to said end and side walls; a follower in said case; resilient means adapted to hold said follower against said ledges; a cover adapted to close 100 said open top; and means to hold said follower away from said ledges comprising a catch and a movable latch adapted to be moved by gravity to and from the path of said catch for the purpose set forth. 105

In testimony whereof, I have hereunto set 110 my hand at Los Angeles, California, this 21st day of December, 1921.

CARL BJORK.
